UNITED STATES PATENT OFFICE.

ELIJAH J. DEVENS, OF COLDWATER, ASSIGNOR OF TWO-THIRDS TO JAMES S. DEWEY AND CHARLES E. YOUNG, BOTH OF DETROIT, MICHIGAN.

FENCE-POST.

SPECIFICATION forming part of Letters Patent No. 361,001, dated April 12, 1887.

Application filed February 3, 1887. Serial No. 226,346. (No model.)

To all whom it may concern:

Be it known that I, ELIJAH J. DEVENS, a citizen of the United States, residing at Coldwater, in the county of Branch and State of Michigan, have invented certain new and useful Improvements in Fence-Posts; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to the general construction of a metallic fence-post made in two sections and in the manner of anchoring the wires to said post, the object being to construct a cheap and lasting fence, and one that 20 may be readily put up or removed; and my invention consists in the construction of parts as hereinafter set forth, and indicated particularly in the claims.

In the drawings, forming a part of this specification, Figure 1 shows a section of fencing containing my invention. Fig. 2 is an enlarged perspective of the fence-post. Fig. 3 shows the lower end of the body of the post. Fig. 4 is a perspective of the head or base. 30 Fig. 5 is a perspective of the metal link for binding the wire to the post.

In the drawings, P represents the post, which is composed of two parts—the body B and base or head H. Said parts are made of 35 sheet metal, preferably sheet-steel.

The body of the post is V-shaped in cross-section. The side wings or flanges, a a, are flat, and are cut away at the lower end, forming the shoulders e e. (See Fig. 3.) The holes 40 2 2 at the lower end are for rivets or bolts to attach the body to the base H of the post, which has also corresponding holes, 2.

I form in the angle of the body B a series of openings or holes, d, by punching out of 45 the body or bending over upon itself the metal, forming the strengthening-flanges i i.

n represents the strands of fencing-wire,

which I secure to the post by means of the link D, which consists of an oblong closed link folded at the center, the free ends forming the 50 mouth m. The link is then placed astride the wire n. Its free ends are passed through an opening, d, of the post. Then, by inserting the wedges S through the free looped ends of the link at the back of the post and within the 55 angle, and by driving down on the wedge, the link D is caused to grasp the wire strand n at two points, thus forming a double-link fastening, as shown in Figs. 1 and 2.

The base H of the post is formed from a 60 single sheet of metal, and in the blank is of a triangular form. The wings Z Z have a tapering edge, t, and at the center, as shown at x of Fig. 4, the wings start from each other at right angles. Each wing is concavo convex 65 in cross-section, as shown in Figs. 2 and 3.

The form is to enable the base to freely enter the soil, (especially in clay soil,) and to form a strong support when driven in. The lower end of the base at f is S-shaped in cross-section. 70

The post is to be driven into the soil, thus dispensing with the digging of a hole for its insertion.

When the soil is very hard, the body B may 75 be detached from the base, and by placing on the upper end of the base a lead or wood follower the base may be easily driven into the ground, when the body may be attached by means of bolts or rivets through the holes 2. 80

It will be observed that the sides 5 5 of the post stand at right angles to each other. The holes d, formed in the angle of the post, give the wires or strands n two bearings. The doubled link D has two bearings on the strand 85 n, and has also two bearings on the wedge S, thus forming a strong and cheap fastening.

Having set forth my invention, what I claim as new, and desire to secure by Letters Patent, is—

1. The metallic fence-post consisting of the part B, V-shaped in cross-section, and having the series of perforations d, and flanges a a, having the shoulders e e, in combination with 90

the base *H*, having the tapering wings *Z Z*, concavo-convex in cross-section, and bolts or rivets for attaching said parts, as specified.

2. The metal post consisting of the part *B*, 5 *V*-shaped in cross-section, and having the series of perforations *d*, with turned-over portions *i i*, the flanges *a a*, having shoulders *e e*, and the base *H*, made of sheet-steel, and

adapted to be attached to the part *B*, as and for the purposes specified.

In testimony whereof I affix my signature in presence of two witnesses.

ELIJAH J. DEVENS.

Witnesses:

A. S. CHAMBERLIN,
TERENCE B. CLARKE.
